RIVET SETTING TOOL

Richard Wadler, Lexington, Mass., assignor to United Shoe Machinery Corporation, Boston, Mass., a corporation of New Jersey

Filed Sept. 28, 1964, Ser. No. 81,889

Term of patent 14 years

(Cl. D54—10)

Fig. 1

Fig. 2

Fig. 3

Fig. 4

FIG. 1 is a view in right side elevation of a rivet setting tool embodying the new design;

FIG. 2 is a bottom end view of the tool;

FIG. 3 is an end view of the tool looking from the left of FIG. 1; and

FIG. 4 is a right hand perspective view of the tool as seen from above.

The dominant features of the design reside in the portions shown in full lines.

I claim:

The ornamental design for a rivet setting tool, substantially as shown and described.
